LUBRICATING MEANS, MORE PARTICULARLY FOR LOCOMOTIVE WHEEL FLANGES

Olof W. Swanson, Chicago, Ill.

Application April 15, 1948, Serial No. 21,126

2 Claims. (Cl. 184—3)

1

This invention relates to lubricating means more particularly for locomotive wheel flanges.

The present invention when employed in connection with the lubrication of the wheel flanges of a railroad locomotive is an improvement on my prior Patents Nos. 1,942,847 of January 9, 1934, and 2,203,112 of June 4, 1940.

Among other objects, the present invention aims to provide improved lubricating means including an intermediate well of lubricating fluid between a reservoir and a delivery pipe, which well of fluid is substantially free from atmospheric pressure when it is not desired that fluid flow from the reservoir, means for restricting passage of oil from the well to the delivery pipe serving to cause accumulation of fluid in the well while permitting limited discharge of fluid therefrom under predetermined conditions.

These and other objects and advantages will be apparent from the following description, taken together with the accompanying drawings, of an illustrative embodiment of the invention, and in which drawings—

Figure 1 is a somewhat schematic view showing a wheel flange oiler, generally in accordance with disclosures of my said patents, and having the present invention incorporated therein; and

Figure 2 is an enlarged vertical section of parts shown in Figure 1 and embodying the present invention.

Referring in detail to the illustrative construction shown in the drawings, the numeral 11 indicates a conventional locomotive driving wheel having the usual flange 12 which is desired to be lubricated with an adequate but not too large amount of oil for the purpose of preventing unnecessary noise and wear and sometimes climbing of the flange on the rail. In accordance with my said Patent 1,942,847, the oil reservoir tank 13 may be provided which may be carried by a bracket 14 suitably secured to the locomotive truck frame, and, in accordance with my said Patent 2,203,112, an oil distributor shoe 15 may be provided in communication with the reservoir 13 and in delivery relation to the wheel flange 12 as by being carried by bracket 16 also suitably mounted on the locomotive truck frame.

In accordance with the present invention, improved means are provided, as here disclosed, for placing the reservoir tank 13 in communication with the delivery shoe 15.

As here shown, subjoined to the reservoir tank 13, in this case as by being formed integrally

2

therewith, is a well casing 17 depending centrally at the bottom of a sump portion 18 of the tank. This well casing 17 is somewhat in the form of a T-coupling having a hollow interior 19 and in this instance a plurality of horizontal tapped openings extending from three sides of the casing as at 20, 21, and 22, there thus being in this instance three such openings, two extending longitudinally of the wheel 11 in opposite directions, and one extending laterally outwardly of the wheel. Such horizontal opening is omitted on the face of the well casing 17 next adjacent the attachment bracket 14. In its bottom face, the well casing 17 has another opening 23 which is normally closed by a drain screw-plug 24 which may be removed for cleaning purposes.

Normally only one of the horizontal openings 20, 21 and 22 is used at a given time, that one in this instance being the opening 20 and the other two horizontal openings 21 and 22 being closed by screw plugs 25.

As here shown, in the horizontal opening 20 is secured means for limiting passage of oil from the well 19 of the well casing 17, and, as here shown, this last mentioned means comprises an oil supply moderator device indicated generally by the numeral 26, extending horizontally from the well 19, and next described.

The moderator device tube 27 is exteriorly threaded at one end as at 28 to be screwed into the horizontal opening 20. The tube 27 at its end farthest from the opening 20 has an enlarged bore 29 and at its other end a greatly reduced bore 30. In the reduced bore 30 plays one end of a wire-like rod member 31, which is shorter than the tube 27 as a whole but longer than the reduced bore 30. The end of the wire-like rod member 31 which projects into the enlarged bore 29 is threaded as at 32 to have screwed thereon a stop member in the form of a nut 33 which limits movement of the rod member 31 in one direction in the bore 30. To limit movement of the rod member in the opposite direction, a nipple 34 having the external thread 35 is screwed into the threaded mouth 36 of the tube 27. Beyond the threads 35 and within the enlarged bore 29 the nipple 34 has a reduced end 36. In this reduced end are a pair of lateral perforations 37 which communicate with the passageway 38 in the nipple, opening into its outer end but stopping short of the extremity of its inner reduced end 36. Thus the disc-like face 39 of the nipple inner end provides an abutment surface which limits

movement of the wire-like rod member 31 in the reduced bore 30.

It will be understood that, as best seen in Fig. 2, the adjacent portion of the wire-like rod member 31 loosely fills the bore 30 and has permissible longitudinal or axial movement as well as rotary movement in this bore, an extreme end of the rod-like member normally projecting inwardly into the well 19.

The periphery 40 of the nipple 34 is desirably of reduced diameter with respect to the diameter adjacent thereto of the tube 27 whereby oil delivery pipe 41, which may be, say, of rubber composition, or other flexible material, may be passed over the nipple periphery 40 and pressed onto the adjacent end of the moderator tube.

The nipple periphery 40 may be of polygonal contour to facilitate screwing of the nipple into the tube, and similarly the tube may have a polygonal formation as at 42 for facilitating screwing of the tube into the tapped opening 20.

To admit the lubricating fluid such as oil from the tank 13 into the well 19, a ball valve device is provided comprising the valve cage 43 which has a threaded outlet 44 which screws into the tapped bore 45 communicating between the sump portion 18 of the tank 13 and the well 19 of the well casing 17, this outlet 44 being centrally pierced as by the duct 46.

The upper end of the duct 46 is normally closed by a ball valve 47 held loosely within the valve cage 43 upon a slightly concave or conical valve seat 48, to which the duct 46 is central. Oil is admitted from the reservoir 49 of the tank 13 as through opening 50 on opposite sides of the valve cage 43.

As described and claimed in my said prior Patent 1,942,847, the openings 50 may be partially filled by a loosely fitting shaft 51 having a propeller-like member 52 thereon which is actuated by agitation of the oil in the reservoir under the influence of vibration of the locomotive when the latter is in motion, thus permitting a limited supply of oil to pass into the valve cage 43, a further limited supply being permitted to pass past the ball valve 47 when the latter is moved on the seat 48 by vibration of the locomotive. Otherwise, the oil has no entry into the valve cage 43 which is closed at its top as by a cap 53. Oil may be replenished in the tank 13 by a removable closure 54 therefor.

Operation of the device of the present invention is as follows:

As a limited supply of oil passes down the duct 46, it is received within the well 19 until the latter fills up to a height which may be indicated say by the line 55, which may be a point just slightly above the reduced bore 30 of the moderator 27, thus immersing the wire-like rod 31 in the oil in the well. Here a limited amount of oil is permitted to pass from the well 19 into the reduced bore 30 of the moderator tube and from thence into the enlarged bore 29 of the tube. Here again the oil is permitted to accumulate until it rises to a point above the transverse perforations 37 in the nipple inner end 36 whereupon the oil flows through the passage 38 in the nipple into the pipe 41 and thence by gravity to the shoe 15, which as described and claimed in my said Patent No. 2,203,112 may include a pair of fingers 56 and a delivery rod 57 therebetween which is in communication with the pipe 41 to receive oil therefrom and let it run down onto the flange 12 of the locomotive wheel 11.

Following the present invention, the operation

is such that a well of oil is maintained in the well casing 17 and this oil therein has limited outlet therefrom by reason of the moderator device 26 providing a restricted passageway therefrom. At the same time the reduced bore 30 is prevented from clogging by the free play therein both axially and rotatively of the wire-like member 31, movement of which again is caused both by flow of oil therearound and by vibration of the locomotive in motion. The degree of longitudinal movement of the wire-like member 31 is limited by the nipple abutment so that one end of the wire-like member always projects to some extent into the well 19 to keep the bore 30 open and unclogged at that end.

Sediment sumps are provided at various stages in the progress of the oil from the tank to the wheel, such as at 18 as already mentioned, again at 58 in the well 19, and again within the bore 29 of the moderator device.

So constructed and arranged oil is delivered to the parts to be lubricated uniformly, under all weather conditions, in winter and summer, without waste of oil. This is particularly important in winter when it may be the practice of railroad maintenance personnel to dilute the oil in the reservoir to keep it from thickening under the influence of cold. Without my present invention such diluted oil may flow too freely and not only cause a waste of the latter but may also cause an over-lubrication of the wheel flange with attendant reduction of traction and waste of power.

The moderator may be designed with a fixed opening and wire-like member therein of an appropriate size to feed a pre-determined number of drops of oil required per minute for lubricating a particular wheel flange under given service conditions. For other service conditions, a different moderator may be inserted to feed more or less oil as required. Both the diameter and length of the reduced bore 30 of the moderator may be varied (in thousandths of an inch) in different installations to accomplish given rates of oil delivery, e. g. as little as one-half pint per wheel flange in 24 hours of locomotive service time.

It will be understood that when the locomotive comes to a stop and the agitation ceases, the oil stops feeding instantly since the ball valve 47 then remains stationary on its seat 48 and closes the duct 46. At this time the oil standing within the well 19 is shut off from atmospheric pressure from above the oil level 55 and such atmospheric pressure as may be exerted is through the delivery pipe 41 and moderator device which counteracts the tendency at such time for oil to pass from the well through the bore 30 to the delivery pipe. When, however, the locomotive again starts up, oil starts feeding immediately since the ball valve 47 is moved on its seat 48 to open the duct 46. At the same time, when the ball valve is off its seat, limited atmospheric pressure is effective on the oil in the well 19 to cause discharge of oil to the delivery pipe.

Since there is no head of oil in the well, there is no more pressure thereon when the tank is full than when it is almost empty, thus insuring uniform feed.

If desired, another moderator and pipe may be secured in one of the other horizontal openings in the well casing, for the same or a different wheel flange or even other locomotive part desired to be lubricated.

The installation as here specifically illustrated

is specially adapted for diesel switchers where

head room is limited between the truck frame 100 and the locomotive underframe (not shown).

The invention is not intended to be limited to details of construction here shown for purposes of exemplification. Furthermore, it is to be understood that all features of the invention need not be used conjointly at all times since various combinations or sub-combinations may at times be advantageously employed. Such changes may be made as fall within the scope of the appended claims without departing from the invention.

The invention having been described, what is here claimed is:

1. In wheel flange lubricating means, an oil supply moderator comprising a tube having an enlarged bore at one end and a greatly reduced bore at its other end, a wire-like rod in said reduced bore loosely filling the bore and materially projecting from the bore at both ends, a stop member on the rod within the enlarged bore limiting outward movement of the rod in the reduced bore, a nipple threaded into the mouth of the enlarged bore, a diametrically reduced inner end on the nipple, said reduced end having an abutment surface for the rod limiting inward movement of the rod in the reduced bore, said rod having play between said stop member and said abutment, a lateral perforation in said reduced end, and a passageway through the nipple spaced from the place of abutment of the rod thereon, and communicating with said lateral perforation.

2. In wheel flange lubricating means, an oil supply moderator comprising a horizontally disposed tube having an enlarged bore at one end and a greatly reduced bore at its other end, a wire-like rod in said reduced bore loosely filling the reduced bore and materially projecting from the reduced bore at both ends, a stop member on the rod within the enlarged bore limiting outward movement of the rod in the reduced bore, a nipple threaded into the mouth of the enlarged bore having an abutment surface for the rod limiting inward movement of the rod in the reduced bore, said rod having play between said stop member and said abutment, and a passageway for oil through the nipple spaced from the place of abutment of the rod thereon.
